UNITED STATES PATENT OFFICE

149,177

DESIGN FOR A COMBINED KNIFE HOLDER
AND TOWEL RACK

John T. Generale, Pelham Manor, N. Y.

Application October 1, 1946, Serial No. 133,678

Term of patent 3½ years

(Cl. D44—29)

To all whom it may concern:

Be it known that I, John T. Generale, a citizen of the United States, residing at Pelham Manor, in the county of Westchester and State of New York, have invented a new, original, and ornamental Design for a Combined Knife Holder and Towel Rack, of which the following is a specification, reference being had to the accompanying drawing, forming part thereof.

Fig. 1 is a front elevational view of a combined knife holder and towel rack, showing my new design, with the towel rods in retracted position.

Fig. 2 is a side view thereof.

Fig. 3 is a top view thereof.

Fig. 4 is a bottom view thereof.

Fig. 5 is a view similar to Fig. 2, but showing the towel rods in extended position.

Fig. 6 is a view similar to Fig. 3, but showing the towel rods in extended position.

I claim:

The ornamental design for a combined knife holder and towel rack, substantially as shown.

JOHN T. GENERALE.
